United States Patent Office.

AZEL LANE, OF ADDISON, NEW YORK.

Letters Patent No. 79,359, dated June 30, 1868.

IMPROVED MACHINE FOR DRESSING MILLSTONES.

The Schedule referred to in these Letters Patent and making part of the same.

TO ALL WHOM IT MAY CONCERN:

Be it known that I, AZEL LANE, of Addison, in the county of Steuben, and State of New York, have invented a new and useful Improvement in Millstone-Dressing Machines; and I do hereby declare that the following is a full, clear, and exact description thereof, which will enable others skilled in the art to make and use the same, reference being had to the accompanying drawings forming part of this specification, in which—

Figure 1 represents a plan view of my improved machine.

Figure 2 represents an end view of the same.

Similar letters of reference indicate like parts.

The nature of my invention relates to improvements in machines for dressing millstones, whereby it is designed to provide a simple, cheap, and effective means for accomplishing the same.

It consists in the arrangement of a horizontal shaft, which forms the axle of the pick-handle, and which is provided with pinions on each end, in a pair of sliding head-blocks, which are caused to move back and forth on a platform by means of the said pinions, which mesh into rack-bars, fixed on the face of the platform. The said bars also serve as guides for the head-blocks, the motion being communicated to the said pinions by a hand-wheel on the end of the shaft, or by a worm-gear on a counter-shaft, as will be more fully described on reference to the accompanying drawings.

A represents a platform, provided with rack-bars B B, which are formed so as to provide the dove-tail grooves a a.

C C represent sliding blocks, which support the horizontal shaft C', on which latter the pick-handle D is pivoted. The shaft C' is provided with the pinions E E, which gear into the rack-bars B B. The blocks C C are rigidly connected together by the rods b b.

The shaft is provided at one end with the hand-wheel F, by which it may be rotated, or a worm-wheel, G, provided with a crank, H, may be fixed to gear into the pinions E for the same purpose.

The pick-handle D is arranged so as to slide loosely on the shaft C', and is operated to pick the stone, by the hand of the operator applied to the shank of the pick. It is also moved from side to side on the shaft C' by the same hand, and at the same time that it is being worked to pick the stone, while by the other hand the shaft C may be rotated to draw the pick over the face of the stone in the opposite direction to the line of traverse of the pick on the handle.

The platform A may be made of iron or wood, and should be provided on the under side with rubber, or other similar material, that will not slip about on the face of the stone.

Having thus described my invention, I claim as new, and desire to secure by Letters Patent—

The combination, with the platform A, provided with the rack-bars B, of the shaft C', provided with the sliding blocks C C and pinions F, substantially as and for the purpose set forth.

AZEL LANE.
